UNITED STATES PATENT OFFICE.

HENRY C. GRAYBILL AND ADOLPH C. ERGLER, OF ALTOONA, PENNSYLVANIA.

FACE-MASK.

1,077,272.

Specification of Letters Patent.

Patented Nov. 4, 1913.

Application filed December 16, 1912. Serial No. 737,158.

To all whom it may concern:

Be it known that we, HENRY C. GRAYBILL and ADOLPH C. ERGLER, citizens of the United States, residing at Altoona, in the 5 county of Blair and State of Pennsylvania, have invented certain new and useful Improvements in Face-Masks, of which the following is a specification.

This invention relates to the subject of 10 face masks of the type generally employed by firemen, or other persons whose duties require their faces to come in contact with intense heat, and also for use by those whose duties require them to work in abnormal atmospheres.

To this end the present invention contemplates a device which provides convenient and efficient means of protecting the face and filtering the air before it enters the 20 lungs of the wearer.

Therefore, the object of the present invention is to provide a face mask which can be worn with a great degree of comfort, since it provides cushioned parts to contact with 25 the face of the wearer and also provides ample space in the front of the mask, which is covered by a transparent element, to enable the wearer to easily see to perform his work. The mask also provides an air chamber in front of the face which is automatically exhausted of its foul contents, and in 30 turn receives a supply of fresh air.

With these and other objects which will more readily appear as the description of the 35 case proceeds, the invention consists in the novel construction, combination, and arrangement of parts hereinafter more fully described, illustrated, and claimed.

A preferred and practical embodiment of 40 the invention is shown in the accompanying drawings, in which:—

Figure 1 is a front elevation of the present invention adjusted to the head of a person. Fig. 2 is a side elevation of the same. Fig. 45 3 is a vertical section of a modification of the invention applied to the face of a person. Fig. 4 is a detail sectional view of the cushion element. Fig. 5 is a detail elevation of the outlet valve. Fig. 6 is a sectional 50 view of the exhaust valve.

Referring specifically to the several figures of the drawings, the numeral 1 designates the body of the mask which is of a shape that conforms with the general features of 55 the human face. The said body 1 is preferably made of aluminum, though other ma-

terials may be used with advantage, and is provided around the outer edge thereof with an annular recess 2 which has formed in the wall thereof a plurality of openings 3. The frame 1 also has suitably located around the outer edges thereof the eyes 4, through which are passed suitable attaching straps 5, which are designated to fit over the head of the wearer and hold the mask in place.

Located within the annular recess 2 is an elastic tube 6 which is provided with the valve 7 in order that it may be inflated and thereby form a cushion, which will snugly fit the face of a person using the mask and prevent smoke or bad air from entering under the side edges of the mask. The said tube 6 is provided with a plurality of resilient projections 8 which are provided with a central cavity 9. These projections 8 are 75 adapted to enter the openings 3 in the wall of the recess 2 and receive in their central cavity 9 a screw 11 or equivalent wedging element. The effect of the screw 11 upon being forced in the cavity 9 is to press the side 80 walls of the projections into engagement with the walls of the hole 3, thereby holding in place the inflated cushion tube 6. In connection with the tube 6, it will be observed that there is a felt or equivalent lining 10 interposed between the tube and the body to prevent the rubber from coming in 85 direct contact with the metal of the body.

The front of the body portion 1 is provided with an opening which extends approximately across the entire front of the upper part thereof, and is fitted with a transparent element 12. This transparent element which may be of glass or mica is held in place by an annular retaining bead 90 13 which is in turn secured to the body 1 by the screw 14. Just below the central portion of the opening in the body 1 there is provided a fresh air intake opening 15, the walls of which terminate in a bead portion 16. There is fitted over the bead 16 a filtering cup 17 which is designed to contain a suitable filtering medium 18. It will be observed that this filtering connection comes at a point which is approximately opposite 105 the mouth of the person wearing the mask, which gives him free access to the fresh air drawn in by inhalation.

Off to one side of the fresh air intake, there is provided an exhaust opening 19 110 which is adapted to be covered by the spring-pressed valve head 20. In order to

prevent the valve from coming too far off its seat on the body 1, there is fitted over the top thereof a cover 21. This valve, of course, only allows air exhausted from the 5 lungs to escape and prevents any foul air from entering at this point.

In the modification illustrated in Fig. 3, instead of a filter cup such as is used in the other application of the invention, the 10 intake opening 15 has attached thereto a tube 22 which extends to a suitable source of fresh air supply, not shown.

From the foregoing description, the many 15 advantages of the present invention will be readily understood without further comment.

We claim:

1. A face mask comprising a body provided with an opening in the front thereof, 20 and an annular recess having a wall provided with a plurality of openings, a tube adapted to be inflated and thereby form a cushion located in said annular recess, resilient projections provided with a central cavity, 25 said projections adapted to enter the openings in the wall of said annular recess, means for entering the cavity of said projections and expanding the same into firm

engagement with the walls of the openings in the recess, a fresh air supply inlet, an exhaust valve, and head attaching means. 30

2. A face mask comprising a body provided with an opening in the front thereof, and an annular recess having a wall provided with a plurality of openings, a tube adapted to be inflated and thereby form a cushion located in said annular recess, means on said tube for entering the openings in the wall of the recess, means for attaching the tube to the body of the mask, a transparent 40 element fitted to the body and covering the opening in the front thereof, means for holding the said element in place, an air intake member containing a filtering medium associated with the body, an exhaust valve 45 comprising a spring pressed valve head, and a cover therefor, and means for securing the mask to the head of the wearer.

In testimony whereof we hereunto affix our signatures in the presence of two witnesses. 50

HENRY C. GRAYBILL.
ADOLPH C. ERGLER.
